UNITED STATES PATENT OFFICE.

JACOB A. SOFFA, OF DETROIT, MICHIGAN.

SAFETY IRON PRESSING SUPPORT.

Application filed February 16, 1926. Serial No. 88,627.

My invention is a pressing iron support and its principal object is to provide a support for normally holding an iron in an elevated position above an ironing board or 5 table where it can be readily grasped and arranged in a position for pressing.

A further object of the invention is to provide a pressing iron support which will permit free movement of the iron in any desired direction and which when the iron is 10 not in use will automatically lift the iron from elevated position.

With the preceding and other objects and advantages in mind, the invention consists 15 in the novel combination of elements, constructions and arrangements of parts and operations to be hereinafter specifically referred to, claimed and illustrated in the accompanying drawings, wherein:

20 Figure 1 is an elevation of a pressing iron support constructed in accordance with my invention, and arranged over a pressing table.

Figure 2 is an end elevation of the device 25 and table.

Figure 3 is a view partly in elevation and partly in section showing the normal position of the iron supporting means.

Figure 4 is a similar view showing the 30 iron supporting means in position when the iron is lowered.

Figure 5 is a fragmentary detail view taken on line 5—5 of Figure 4.

Figure 6 is a similar view on line 6—6 35 of Figure 4.

Figure 7 is a detail sectional view of one of the carriages embodied in the invention.

Figure 8 is a perspective view of the frame for the device.

40 Referring to the drawings in detail wherein corresponding characters of reference denote corresponding parts throughout the several views, the numeral 5 designates a frame constructed from a length of pipe 45 or tube and including a pair of vertical legs 6 at one end and a single vertical leg 7 at its opposite end and a pair of horizontal parallel rods 8 connecting the legs. The legs 6 and 7 pass through straps 9 arranged

50 upon the ends of a table indicated at T and are provided with plates at their lower ends which are adapted to be attached to the floor as shown. Bridging the legs 6 are a pair of cross members 5' which have secured mid- 55 way their ends brace rods 6' adapted to be secured at their opposite ends to a substan-

tial supporting means in a manner whereby clothes may be hung thereon. The upper rod 6' may be used for pressed clothes, while the lower rod may be used for clothes to be 60 pressed.

Slidably mounted for movement longitudinally with respect to the rods 8 is a pair of carriages 11 each of the carriages comprising a pair of opposed plates 12 having semi-circular parts 13 which embrace sleeves 8' surrounding the rods 8 for movement thereon. These plates 13 are secured together by removable fastenings 14. Extending transversely of the carriages 11 and having their ends received therein is a pair of stationary shafts 15, the latter having their inner ends rotatably received in bearings 16 formed on a plate 17, the latter being made in sections 18 which are bolted together by means of bolts 19. Formed with the plate 18 extending at right angles to the bearings 16 is a sleeve 21 which receives a longitudinally adjustable pressing iron supporting rod 22, the latter being capable of 65 longitudinal adjustment in the sleeve 21 and retained in adjusted position by means of a set screw 22' carried by the sleeve 21. A counter-balancing weight 23 is mounted for longitudinal adjustment on the rear end 70 of the rod 22, the weight being provided for the purpose of accommodating different sizes of irons.

An iron supporting rod is designated at 75 24 and is provided with a lower hook 25 to engage the iron hanger as shown in full lines and a vertically adjustable hook 26 to retain the iron at a higher elevation when the press board P is in use on the table. The upper end of this rod 24 is attached loosely to the eye 27 carried by the forward end of the rod 22 and by this loose connection the iron can be moved laterally.

In order to lock the rod 22 in a position shown in Figure 4 there is provided a U-shaped member 29 whose ends are carried by the carriages 11 and carried by the U-shaped member is a pair of resilient clips 30 between which the rod 22 engages and is held in position as shown in Figures 4 and 5. 80 A contractile spring 31 embraces the rod 22 at a point in advance of the bearings 16 and has its ends attached to eyes 32 carried by the shaft 29. The function of this spring is to prevent the rod 22 from swinging beyond 85 the position shown in Figure 1 when the device is in operative or supporting position.

The clips 30 are adapted to aid in holding the iron in pressing position, so that very little effort is necessary for this purpose, as it will be obvious that if the weight 23 constantly exerted all its capacity against the iron, considerable effort would be experienced in holding the iron in its working positions. A slight upward pull upon the iron will release the rod 22, with the result that 10 the weight 23 will dispose the iron in the position as shown in Figure 1.

From the disclosure it will be seen that the iron can be moved back and forth and laterally on the ironing surface without any interference whatsoever and be retained at a 15 convenient point above the table when not in use. This will lessen the work of the tailor or any one using the same and at the same time the device can be installed in any desirable place.

While I have shown and described the preferred embodiment of the invention, I desire to have it understood that such changes may be made in the form, construction, arrangement of parts and operations as will not depart from the spirit of the invention or the scope of the subjoined claims.

What is claimed is:—

1. A pressing mechanism of the character 30 described comprising a frame including legs and parallel bars, brace means for said legs and bars, carriages mounted for slidable movement on said parallel bars, shafts secured to and extending inwardly from said

carriages, plates pivotally secured to the inner ends of said shafts, a sleeve formed with said plates, a rod mounted for longitudinal movement in said sleeve, means for adjustably securing said rod in said sleeve, a counter-balancing weight upon one end of 40 said rod, and a pressing iron suspension element swingingly depending from the opposite end thereof.

2. A pressing mechanism of the character described comprising a frame including legs 45 and parallel bars connected thereto, brace means for said legs and bars, carriages slidably mounted on said bars, shafts extending inwardly from said carriages, plates pivotally secured to the inner end of said shafts, 50 a sleeve formed with said plates, a rod mounted for longitudinal movement in said sleeve, means for securing said rod in said sleeve and carried by said sleeve, a counter-balancing weight adjustably secured to one 55 end of said rod, a pressing iron suspension element depending from the opposite end of said rod, a U-shaped member secured to said carriages, spring clips secured to the U-shaped member and arranged in the path of 60 the rod for holding the same in a substantially horizontal position, a contractile spring embracing the forward end of said arm and having its ends fixed to the U-shaped member and serving to limit the 65 movement of the arm in one direction.

In testimony whereof I affix my signature.

JACOB A. SOFFA.
